UNITED STATES PATENT OFFICE

168,060

LAMP

Martha M. McDevitt, Atlanta, Ga.

Application November 23, 1951, Serial No. 17,500

Term of patent 7 years

(Cl. D48—20)

To all whom it may concern:

Be it known that I, Martha M. McDevitt, a citizen of the United States, residing at Atlanta, in the county of DeKalb and State of Georgia, have invented a new, original, and ornamental Design for a Lamp, of which the following is a specification, reference being had to the accompanying drawings, forming a part thereof.

The dominant features of my design are shown in full lines.

I claim:

The ornamental design for a lamp, as shown and described.

MARTHA M. McDEVITT.
